UNITED STATES PATENT OFFICE.

FREDERICK REUTER, OF BROOKLYN, NEW YORK, ASSIGNOR TO JOHN C. GRAHAM, OF PHILADELPHIA, PENNSYLVANIA.

DESIGN FOR FRINGE.

SPECIFICATION forming part of Design No. 13,096, dated July 25, 1882.

Application filed June 16, 1882. Term of patent 14 years.

To all whom it may concern:

Be it known that I, FREDERICK REUTER, of Brooklyn, in the county of Kings and State of New York, have invented and produced a new and original Design for Fringe, of which design the following is a specification.

The accompanying drawing is a side view of a section of fringe embodying and illustrating my design, which consists in a fringe having a heading, A, to which is attached a series of chenille pendants, B, ornamented by the following arrangement of colors in the threads of which they are composed, to wit: The upper portion, b, and the lower portion, b', of the pendant are each graduated, shaded, or varied in depth or intensity of any selected color from one end to the other, the greatest depth of color being at the heading and at or near the free end of the pendant, respectively.

Between these two gradations of color—that

is, at about the middle of the pendant—there is interposed a block or bar, b², of a color different from that of the portions b and b', said block being preferably shaded or varied in depth of color from its center to each of its ends. The addition of an end swell or enlargement, b³, of a different color from that of the portion b' is optional, and will not affect the distinguishing characteristic of the design.

I claim—

A design for fringe, consisting of pendants presenting a shading, graduation, or tinting of color from each end toward the center, and an interposed middle block or bar of a different color, substantially as set forth.

FREDERICK REUTER.
